[57] CLAIM

The ornamental design for a panel unit for a work station, as shown and described.

DESCRIPTION

FIG. 1 is a perspective view of a panel unit for a work station showing my new design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a front elevational view thereof;

FIG. 7 is a perspective view, the showing of broken line matter is for illustrative purposes only and forms no part of the claimed design;

FIG. 8 is a top plan view thereof.
